UNITED STATES PATENT OFFICE.

JOSEPH SALTZMAN AND FRITZ HERMAN LANGE, OF CHICAGO, ILLINOIS; SAID LANGE
ASSIGNOR TO SAID SALTZMAN.

TAPE SPONGING AND SHRINKING MACHINE.

Application filed April 16, 1927. Serial No. 184,205.

This invention relates to a novel tape sponging and shrinking machine, adapted for wetting tape, such as used in making garments and in shrinking the same before use, so that the garments will retain their shape and fit, and will not wrinkle and lose their form due to shrinking of the tape with respect to the cloth of the garment in use or should the same get wet in inclement weather.

10 Among the objects of the invention are to provide a sponging machine which may be motor-driven or hand-operated, and is adapted to receive the usual tape spool and a reel upon which the tape is reeled or wound as it is unwound from the spool and passed through water in a tank forming a part of the machine; to provide a wringer for removing the surplus water from the tape before re-winding the same on the reel, whereby drying is facilitated and rendered possible in a much shorter length of time than could otherwise be secured but without impairing the proper shrinking of the tape; to provide for the rewinding of the tape on the spool where this is desired, as well as the proper feeding, threading, and even distribution of the tape either on the reel or on the spool without the necessity of providing complicated and expensive extra devices for this purpose, to provide for the expansion and contraction in the size of the reel, whereby the tape, when wound thereon, may be loosened or slackened to relieve the tautness and tension to permit complete shrinkage and take-up in drying; to provide for convenient mounting and removal of the spools and reels; to provide a reel which will withstand shrinkage tension without bending, and to provide a dryer in connection therewith, or otherwise, for receiving and mounting the reels during the drying operation.

40 Other objects are to provide means to subject the tape on the reels to the action of heat for drying after sponging, using any desired heating medium, such as electricity, gas, hot water, or steam, and for mounting the reels in a dryer for effectively and economically drying the tape, and to provide means for mounting the reels on which the tape is wound in the sponging thereof and in shrinking and drying the same, to permit free turning of the reel and feeding of the tape to the sewing machine in sewing the tape in the

garment directly from the sponging and drying reel, so that re-winding of the tape upon 55 the spool is obviated.

Referring to the drawings in detail:—

Figure 1 is a front elevation of my novel tape sponger and shrinker.

Fig. 2 is a plan view partly broken away 60 and in section on the line 2—2 of Figure 1.

Fig. 3 is a vertical sectional view taken on the section line 3—3 of Figure 1.

Fig. 4 is a fragmentary enlarged detail side elevation of a bearing on the frame for 65 the tape spool shaft.

Fig. 5 is an enlarged axial or central sectional elevation of the tape school shaft showing the spool holding means and spool mounted thereon, the same being partly broken 70 away.

Fig. 6 is a perspective view of a collapsible and extensible reel forming part of the device.

Fig. 7 is an elevation of another reel. 75

Figs. 8 and 9 are transverse sectional views taken on the section lines 8—8 and 9—9 of Figure 7, and

Fig. 10 is a detail sectional view showing a detachable pulley mounting for the reel 80 shaft.

On the drawings, the tape sponger and shrinker comprise an open top tank 15 preferably of rectangular form, adapted to receive the water as at 16 for sponging or wetting the tape. The tank 15 has a frame 17 preferably comprising angle iron members embracing the corners thereof and extended below the bottom of the tank to provide supporting legs 18, whereby the tank is supported above the floor. A drain valve 19 is provided in the bottom of the tank so that the entire contents can be removed and a new supply of water poured into the tank from the top. Mounted on one side of the tank is 95 a shelf or platform 20 held by brackets 21 and adapted to support a motor 22, preferably an electric motor adapted to be connected to a source of current supply by plugging in on the house wiring, or otherwise, as 100 usual.

Mounted transversely on the tank is an upright frame or bearing support 23 including vertical side bars 24 held in upper and lower sockets or clamps 25 secured to opposite sides 105 of the tank. The upright frame extends con-

siderably above the tank and the upper ends of the vertical side bars are connected by a cross bar 26 which braces the side bars in spaced parallel relation and forms therewith a substantially inverted U-shaped structure. For convenience, the upright frame 23 may be formed of pipe sections and the cross bar 26 joined to the side bars 24 by the elbows 27. Mounted on the side bars 24 near the top 10 of the frame are bearings 28 having the lower sleeve portions 29 fixed to the side bars and having concave bearings 30 projecting laterally at one side adapted to receive a tape spool shaft 31. The sleeves 29 constitute the 15 lower sections of the bearings and the upper sections are comprised by sleeves 32 having lateral plate extensions 33 which fit over the shaft 31 and the receiving portions proper 30 and retain the shaft in position while 20 permitting removal of the shaft by turning the sleeves 32 to displace the bearing portions 33 from over the parts 30. The sleeves 32 are adapted to be held in position by set screws 34. 25 The tape spool is indicated at 35, having the tape 36 wound thereon and may be of the usual pasteboard type having wooden cores 37 fitted in the ends thereof, although it is obvious that the spool may be of metal, wood, 30 or other type commonly used for holding tape. When the spool is mounted on the shaft, it is fixed to rotate therewith when the shaft is driven, as will be later described, through the instrumentality of a holding 35 means including a set collar 38 fixed to the shaft by a set screw 39 and a cone-shaped sleeve 40 which engages one end of the spool and frictionally fits in one core 37 and is held by an expandible coil spring 41 mounted on 40 the shaft between the collar 38 and the sleeve 40, so as to force the cone or tapered end of the latter into the core which fits loosely over the shaft. The position of the spool on the shaft may be regulated or centered and the 45 friction determined by adjusting the tension of the spring 41 through the medium of the adjustable collar 38. A similar cone sleeve 42 is also mounted on the shaft to similarly engage in the opposite core and is held by 50 set screw 43, except that this sleeve may have a pin 44 projecting inwardly from the cone end thereof to pierce or project into the adjacent core 37 so as to fix the spool to the shaft and cause it to rotate therewith. One 55 or both ends of the shaft may be provided with a pulley 45 fixed thereto outwardly of the frame.

60 Journalized in bearings 46 in the sides of the frame 23 is a shaft 47 which is positioned considerably below the shaft 31 and the bearings 28 thereof, and on one end of the shaft 47 is a large drive pulley 48 which may be 65 optionally equipped with a handle 49 for turning the same manually, or it may be driven from the motor 22 by a belt or chain

50 trained around the pulley 48 and a small pulley 51 on the rotor shaft 52 of the motor 22. The pulley 51 is relatively small in comparison to the drive pulley 48, so that the latter and the shaft 47 will be driven relatively slowly. A pulley 53 is fixed to the opposite end of the shaft 47 outwardly of the frame 23 in alignment with the pulley 45. These pulleys are preferably of the same size but not necessarily so. 75

The frame 23 immediately above the top of the tank 15 is provided with bearings 54 corresponding to the bearings 28 and is adapted to rotatably receive an extensible and collapsible tape reel 55 through the medium of its shaft 56 which is detachably or removably mounted in the bearings and has detachably fixed to one end thereof a pulley 57 outwardly of the frame and displaced inwardly with respect to the pulley 53 but disposed in alignment with a pulley 58 of still smaller dimensions which is fixed to the shaft 47 immediately inwardly of the pulley 53. 85

An endless belt 59 is adapted to be trained 90 around the pulleys 57 and 58 and the distance between the shafts 47 and 56 is preferably slightly greater than the distance between the shafts 31 and 47, so that the belt 59 may be adapted to fit around the pulleys 45 and 53, whereby the spool shaft 31 may be driven for re-winding the tape on the spool should this be desired, although ordinarily when the belt 59 is trained around the pulleys 57 and 58 the tape reel 55 will be rotated at a reduced 100 speed through its shaft 56. The driving means thus provided constitutes a reducing gear between the motor and the part to be driven. 105

The reel 55, of which any number may be 110 provided to accommodate the necessary supply of tape for sponging and drying, has hubs 60 from which extend spokes or arms 61, preferably four in number, located at right angles to each other, three of which have fixed there- 115 to cross arms or bars 62 which are fixed in spaced relation to the outer ends of the spokes. The other cross bar 63 has sleeves 64 which are radially adjustable on the other spokes or arms 61 and held by set screws 65, 120 thus rendering this reel collapsible or extensible as desired, the purpose being to loosen or slacken the tape 36 when wound on the reel after being sponged or wetted in passing through the water 16, in order to permit the necessary shrinking in drying. 125

When the belt 59 is arranged as shown in Figures 1 and 3 for sponging the tape and winding the same upon a reel 55, the tape 36 is extended around a guide in the form of a roller 66 journaled in brackets 67 secured to one wall of the tank at the inside near the top, the roller being spaced from the inner surface and the tape extending around the roller through said space after extending 130

from the spool in a rearwardly and downwardly inclined position and then in a forwardly inclined position beneath and around a roller 68 journaled transversely in the side walls of the tank so as to pass the tape through the water 16. The tape then extends upwardly and forwardly through a wringer 69 from whence it extends over one of the cross bars or arms 62 of the reel 55 and is secured or anchored to the axis or hub of the reel so as to be wound on the latter and automatically threaded or evenly distributed over the same as the device is operated to wind the tape on the reel by its guidance from the position of the tape as it unwinds from the spool 35.

The wringer 69 is for the purpose of removing the surplus water from the tape, so that the drying and shrinking thereof will take less time and yet accomplish complete shrinkage. It comprises a roller 70 journaled in bearing brackets 71 secured to the inner face of the tank at the wall opposite that on which the roller 66 is carried and in a position below the same. However, the roller 70 is more widely spaced from its carrying wall due to the greater extension of the brackets 71 and co-operating with the roller 70 is another roller 72 which is journaled in a U-shaped frame or bearings 73 from which a pair of threaded stems 74 extend through apertures in the adjacent side wall and frame of the tank and on the outer ends of which a handle 75 is retained by suitable fastening means such as nuts 76. Expansible coil springs 77 are mounted on the stems 74 between the inner surface of the tank and the frame or bearing 73 so as to normally hold the roller 72 pressed against the roller 70 under slight tension sufficient to remove the surplus water from the tape as it passes between the rollers. The tension of the springs 77 may be regulated by the nuts 76 and by pulling outwardly on the handle 75 the tape may be easily passed or threaded between the rollers for connection to the reel in the successive operations of the machine in sponging the spools of tape and in winding the same on the reels after passing the tape through the water for dampening or moistening. The tape is subsequently dried and shrunk by removing the reel from its bearing with the tape wound thereon, after which another reel may be mounted in position on the machine for taking another spool of tape and so on.

One form of dryer which is incorporated with and forms a part of the machine is shown in Figures 2 and 3 which includes an oven or receptacle 78 corresponding substantially to the tank 15, and which may be connected thereto by braces 79. This oven or drier has a frame structure 80 extended to produce legs 81 for supporting the same above the floor and has supports 82 and 83 in opposite end walls to take one end of the shaft 56

of the reel 55 and the pulley 57 mounted on the other end of the shaft so as to accommodate and support the reel in the oven in spaced relation to the top and bottom thereof.

A burner or heater 84 shown of the gas type having a control valve 85 is suspended by brackets 86 from the bottom of the oven, which bottom has a reinforced apertured portion 87 and an apertured burner plate 88 mounted in spaced relation to said bottom as by brackets 89, thus permitting the heat to enter the oven or drier through openings 90 but preventing scorching. A cover 91 is provided on the receptacle or oven 78 and has ventilating slots 92 to permit the escape of moisture or vapor as the water is absorbed. A handle 93 is provided on the cover for convenience in applying or removing the same. Strips or lugs 94 may be equipped on the bottom of the cover to properly position the latter. Of course, it is to be understood as the reels are removed from the machine—that is, the winding or reeling mechanism, they are placed in the oven or drier for the purpose of drying and shrinking the tape, but the reel is collapsed from its extended position by sliding the cross arm 63 inwardly on the radial arms 61 after loosening the set screws 65, so that the tape will be slack or loose and may have complete shrinkage in drying. Otherwise, the tape would be under tension on the reel and would be practically stretched to its original dimensions or prevented from shrinking, and in case the material of the reel is not sufficiently heavy to resist this tension, the arms of the reel would be distorted or bent. This is prevented by the collapsible and expandible feature which is more clearly shown in Figure 6 of the drawings.

In Figures 7, 8, and 9 of the drawings, another form of extensible and collapsible reel is shown which comprises a shaft 95, the ends 96 of which are adapted to be received in the bearings 54, heretofore described. One end detachably carries a pulley 97 corresponding to the pulley 57. Fixed to the shaft are disks 98 constituting the ends of the reel or spool, the same being fixed through the medium of the sleeve portions 99 by set screws or the like 100, although pins or keys or other means for this purpose may be employed. Each disk has a plurality of sleeves 101, preferably four in number detachably mounted thereon and in longitudinal alignment in pairs at opposite ends. These sleeves take pivot pins 102 at the inner ends of arms 103 which are thus pivotally mounted on the disks. The arms are preferably of angular formation as shown, all being bent in the same direction. Fixed to the shaft at one end is a spur gear 104 and the adjacent arms have their inner ends extended and provided with segmental gears 105, the teeth of which mesh with the spur gear 104. The arms 103 are connected by cross arms 106, preferably

two in number and on which the tape is adapted to be reeled in the sponging operation.

Rotation of the shaft, disks, and spur gear 104 with respect to the arms or vice versa—that is, swinging of the arms on their pivots, will result in simultaneously contracting the reel arms from the extended position shown in Figure 9. During this movement the arms will swing angularly on their pivots, thus drawing in the cross arms to collapse the reel for slackening the tape thereon, so that it can properly shrink. In order to hold the arms in the different positions, one of the arms at the end, not provided with the gears, is extended beyond the pivot at 107. This extended end has a projection 108 directed outwardly toward the adjacent disk 98, shown more particularly in Figure 7. A lever 109 is pivoted at 110 to the adjacent disk near the axis and the pivoted end is forked or bifurcated at 111 to receive a coil spring 112, one arm of which engages the lever at 113 and the other arm 114 of which engages a lug 115 on the disk so as to normally urge the lever toward a stop lug 116 also provided on the disk. The lug 116 serves to limit the expansion of the reel as the arms are urged outwardly under the action of a coil spring 117 mounted on one of the sleeves 101 and having one arm engaging the lug 115 as indicated at 118, while the other arm engages the adjacent arm 103 as indicated at 119. Of course, the fact that all the arms are geared together causes them to work simultaneously when expanded or contracted by swinging on their pivots in the manner described under the tension of the spring 117. This movement is limited by the engagement of the pin or projection 108 with the stop lug 116 when the arms are swung outwardly to expand the reel and the projection 108 is released from over a shoulder or detent 120 on the lever 109. When the projection 108 is engaged with the detent 120 the reel is held from expanding or extending, the arms being thus prevented from swinging outwardly owing to the abutment of the projection 108 with the detent as the lever 109 is held over by the spring 112. The lever 109 has a handle 121 extending over the edge of the adjacent disk 98 by which it may be manipulated.

The tank 15 at the side provided with the wringer 69 also may be provided with a removable guard 148 curved upwardly and inwardly slightly over the tank against which the water is thrown from the wet tape on the reel as the latter is rotated to wind the tape thereon. This guard catches the spray of water and prevents the same from being thrown outwardly so that the water will drain back into the tank. The guard is detachably mounted on the top edge of the tank at the front side and for this purpose has an angular strip 149 attached thereto at 150. The offset portion is spaced from the sheet of

metal forming the guard so as to fit over and clamp on the top edge of the front of the tank.

In Figure 10 of the drawings, there is shown a detachable mounting for the pulleys 57 and 97, in which there is secured to each shaft 63 or 95, a sleeve or annulus 151 as by a tapered pin 152 passing through the reduced portion of the sleeve and the shaft. The sleeve is spaced from the end of the shaft and has two pins 153 secured thereto at diametrically opposite points and projecting from the face thereof to engage sockets 154 in the pulley 57 or 97, so that the pulley will rotate with the shaft. The end of the shaft does not extend entirely through the pulley but terminates in spaced relation to the face 155. The shaft has a threaded socket 156 to take a thumb screw 157 so as to secure the pulley in position. The spacing of the end of the shaft from the face 155 permits the screw to frictionally clamp against the pulley at said face, whereby the pulley is firmly secured in position. This would not be possible if the shaft did not terminate short of the face 155, which is the outer face of the pulley when secured in position, as the screw simply clamp against the end of the shaft and the pulley would remain loose. In either detachable mounting of the pulleys, the latter may be removed from the shaft of the reel so that only one pulley will be necessary for a number of reels, and the bearing 83 may be substituted by a bearing similar to the bearing 82 to take the ends of the reel shaft without the pulley thereon.

While we have shown and described our invention in a preferred form, we are aware that various modifications and changes may be made therein without departing from the principles of the invention, the scope of which may be determined by reference to the appended claims.

We claim as our invention:

1. In a tape sponging and shrinking machine, a tank for containing water, a frame on the tank for rotatably supporting a spool of tape above and over the tank, means for supporting a reel in a position over and partly extending into the tank, means for guiding the tape from the spool into the tank for passing the same through the water therein and over the reel for winding the tape on the latter, and means for driving said parts.

2. In a tape sponging and shrinking machine, a tank, a frame on the tank for rotatably supporting a spool of tape, means for supporting a reel over and in position to extend partly into the tank, means for guiding the tape from the spool into the tank at one side, then to a point near the bottom thereof for passing the same through the water therein, then at the other side and under the reel for winding the tape on the latter, means for removing surplus water from the tape during

the reeling thereof, and means for driving the reel to draw the tape from the spool.

3. In a tape sponging and shrinking machine, a tank, a frame on the tank for rotatably supporting a spool of tape, means for supporting a reel over and in position to extend partly into the tank, means for guiding the tape from the spool into the tank at one side, then to a point near the bottom thereof for passing the same through the water therein, then at the other side and under the reel for winding the tape on the latter, said guiding means at the other side constituting means for removing the surplus water from the tape after the same passes through the water and before it is wound on the reel, means for rotating the reel, and means for feeding and distributing the tape uniformly over the reel.
4. In a tape sponging and shrinking machine, a tank, a frame on the tank for rotatably supporting a spool of tape, means for supporting a reel in the tank, means for guiding the tape from the spool into the tank for passing the same through water therein and under the reel for winding the tape on the latter, and means for driving the reel or spool, said means being motor-operated and including a reducing gear, said reel being collapsible.

5. In a tape sponging and shrinking machine, a tank, a frame on the tank for rotatably supporting a spool of tape, means for supporting a reel over the tank, means for guiding the tape from the spool into the tank for passing the same through water therein and under the reel for winding the tape on the latter, means for driving the reel or spool, means for detachably supporting the spool including a shaft having spool-gripping means, and means at one side of the tank for wringing the tape during the reeling thereof.
6. In a tape sponging and shrinking machine, a tank adapted to contain water, an upright frame on the tank comprising a substantially inverted U-shaped structure including side bars detachably mounted intermediately of two opposite sides of the tanks, a cross bar connecting the upper ends of the side bars and bracing the same above the tank, bear-

ings on the side bars for receiving a shaft to support a spool of tape over the tank near the top of the frame, tension means on the shaft and engaging the spool to regulate the unwinding and winding thereof, other bearings on the side bars near the top of the tank for supporting a reel over the tank and in position to extend therewith, means for driving said spool shaft and reel simultaneously, and means for guiding the tape from the spool down into the tank along one side, then down near the bottom of the tank to dip in the water and then up along the other side to connect with the reel.

7. In a device of the class described, a tank having a frame, a spool-supporting shaft detachably mounted in bearings on the frame, another shaft journaled in the frame beneath the first shaft, a motor for driving the second shaft, bearings on the frame immediately above the tank, a reel having a shaft adapted to be detachably mounted in the last-named bearings and to extend into the tank, means for guiding the tape from the spool along one side of the tank and beneath the water therein and then at the other side of the tank for winding the same on the reel, and means for operatively connecting the reel shaft and second shaft for rotating the reel.

8. In a device of the class described, a tank having a frame, a spool-supporting shaft detachably mounted in bearings on the frame, another shaft journaled in the frame beneath the first shaft, a motor for driving the second shaft, bearings on the frame immediately above the tank, a reel having a shaft adapted to be detachably mounted in the last-named bearings and to extend into the tank, means for guiding the tape from the spool along one side of the tank and beneath the water therein and then at the other side of the tank for winding the same on the reel, and means for operatively connecting the reel shaft and second shaft for rotating the reel, one of said guiding means constituting a wringer for removing surplus water from the tape prior to the winding thereof on the reel.

JOSEPH SALTZMAN.
FRITZ HERMAN LANGE.
